PACKAGE ADVANCING MECHANISM

Thorvald Petersen, Erie, Pa., assignor to R. G.
Wright & Company, Buffalo, N. Y.

Application April 21, 1937, Serial No. 138,138

28 Claims. (Cl. 226—76)

This invention relates to improvements in mechanisms for advancing packages or containers, for example, for the purpose of filling and closing such packages.

5 I have shown my invention in the accompanying drawings as applied to a milk bottle filling and capping machine, but it is not intended thereby to limit this invention to such use, since it will be obvious that the mechanism herein described may operate on other packages or containers.

One of the objects of this invention is to provide a package advancing mechanism of improved construction and high efficiency whereby the packages, regardless of their size and the time required for filling them or otherwise operating on the same, may be moved from one position to another at a maximum rate of speed. It is also an object of this invention to provide the mechanism with means for varying the time interval during which the packages remain in a station, without varying the speed of movement of the packages from one station to another.

Another object of this invention is to provide an improved mechanism by means of which a 25 rotary table supporting the packages may be raised and lowered and also moved through an arc of a circle when in lowered position. Another object of this invention is to provide a mechanism which operates intermittently and which is stopped when packages are in position to be operated upon and which is again started in operation after the desired time interval. It is also an object of this invention to provide mechanism of this kind which can be easily and accurately 30 adjusted to vary the time interval during which the mechanism is stopped.

Another object of the invention is to provide improved means for stopping and again starting the mechanism; also to provide means whereby 40 the mechanism can be operated partly automatically and partly under the control of the operator.

A further object of the invention is to provide means of improved construction for imparting 45 rotary motion to the package supporting table; also to provide mechanism of this kind with means for accurately positioning the table so that the packages will be in their correct stations. Other objects of the invention will appear from the following description and claims.

In the accompanying drawings:

Fig. 1 is a perspective view of the bottle filling and capping mechanism in which the bottles or containers are advanced by means of mechanism 55 embodying this invention.

Fig. 2 is a top plan view thereof.

Figs. 3 and 4 are fragmentary elevations, on an enlarged scale, of portions of the machine showing containers of different sizes in their closing or capping positions.

5 Fig. 5 is a fragmentary sectional view of a part of an adjusting lever for varying the time during which the containers remain in filling or closing positions.

Fig. 6 is a central sectional elevation of the 10 filling and capping machine provided with my improved container advancing mechanism.

Fig. 7 is a horizontal section thereof, on line 15 7—7, Fig. 6.

Figs. 8 and 9 are fragmentary elevations of the 20 lower portion of the machine, showing a foot pedal for starting and stopping the machine, in different positions.

Fig. 10 is a sectional plan view thereof, on an enlarged scale, on line 10—10, Fig. 6.

25 Fig. 11 is a sectional elevation thereof, on line 11—11, Fig. 10.

Fig. 12 is a fragmentary sectional elevation thereof, on line 12—12, Fig. 10.

Fig. 13 is a fragmentary sectional plan thereof, 30 on line 13—13, Fig. 6.

Fig. 14 is a transverse sectional elevation thereof, on line 14—14, Fig. 12.

Fig. 15 is a fragmentary sectional elevation thereof approximately on line 15—15, Fig. 10.

35 Figs. 16 and 17 are similar sectional elevations in which the parts are shown in different positions.

Fig. 18 is a sectional elevation thereof, on line 18—18, Fig. 17.

Fig. 19 is a sectional plan view thereof, on line 19—19, Fig. 17.

Fig. 20 is a sectional elevation thereof, on line 20—20, Fig. 19.

In the drawings, I have shown by way of example, a milk bottle filling and capping machine to which my improved container advancing mechanism is applied. This machine includes a base or housing A within which my improved mechanism is confined, the housing being provided with a removable cover a to which access may be had to the mechanism contained in the housing.

The housing or base also serves to support an upright column B at the upper end of which is mounted a tank C for milk or other liquid with which the containers are to be filled. The column B also supports a movable table D on which the containers or bottles are positioned and on this table a plurality of bottle container supports d are yieldingly mounted. The table is rotatable so that the containers after being 50 55

positioned on the supports *d* of the table advance in the first place to a filling station at which a series of valve actuating members *E* are provided which may, for example, operate to fill the containers as described in my Patent No. 2,057,538 of October 13, 1936. After the containers are filled, they are advanced to a capping position or station in which a plurality of capping devices or members *F* are provided which place caps from magazines *f* on the containers. The capping mechanism may, if desired, be constructed in accordance with that shown in my pending application No. 112,106 filed Nov. 21, 1936. The containers after being capped or closed are then moved by the table *D* into a third position or station *G*, Fig. 2, and while in this position, the filled and capped or closed containers may be removed from the machine and replaced by containers to be filled. From the station *G*, these containers are then advanced to the filling station or position.

The table *D* during the operation of the machine is, consequently, subjected to rotary motion through a third of a circle to move the containers from one station to another. Upon completion of the rotary motion the table is raised so that the containers are placed into operative relation to the filling and capping mechanisms. After the completion of the filling or other operation, the table is first moved downwardly and then turned through a third of a circle to advance the containers or bottles to the next station, and then again raised.

I have shown in Figs. 3 and 4, a manner in which the bottle filling and capping machine may be employed for filling bottles of different sizes. For example, in Fig. 3, I have shown a single spacing member *h* arranged on the container support *d*. In Fig. 4, I have shown an additional spacing member *i* positioned on the spacing member *h*. Consequently, when the machine operates on containers or bottles *X* of the maximum size as shown in Fig. 6, the bottles stand directly upon the supports *d*. When the machine is used in connection with bottles or containers *Y* of a smaller size than shown in Fig. 3, only the spacing member *h* is employed and when still smaller bottles or containers *Z* are being operated upon, two spacing members *h* and *i* are employed. For example, the bottles *X* may be quarts, the bottles *Y* pints, and the bottles *Z* half-pints. Any other means for adapting the machine to operate on containers of different sizes may be used.

It will, of course, be understood that my improved mechanism may be used in connection with any other device employed for effecting operations upon articles or containers, the milk bottle filling and capping machine in the accompanying drawings being shown merely by way of example.

It will be obvious from the machine thus far described that when a large container or bottle *X* is being filled, considerably greater time is necessary to fill such bottle than either of the smaller bottles *Y* and *Z*. In order to enable a machine of this type to operate at maximum efficiency, the table or container support *D* should be advanced from one station to another at the maximum speed and such speed is definitely limited for the reason that excessive speeds will either cause the bottles to fall over during acceleration or retardation or movement of the bottle supports or will cause liquids to spill out of the bottles when moving from their filling to

their capping positions. Consequently, in machines heretofore constructed, it was necessary to limit the speed of operation of the machine to the time necessary to fill the largest container on which the machine was capable of operating. Consequently, when the machine was operating on half-pints, the same length of time was required to fill half-pints as to fill quarts. In accordance with my improved mechanism, the machine is so operated that the speed of movement of the table is always the same, regardless of whether the machine is operating on smaller or larger containers, but the time interval during which the containers remain at their various stations may be varied in accordance with the size of the container which is being operated upon. Consequently, it is possible to materially reduce the time required to hold smaller containers in the filling position without varying the speed with which the containers are advanced from one station to another.

In the improved mechanism for producing these results which I have herein illustrated and described, I have incorporated merely one embodiment of this invention, and it will be understood that it is not intended to limit this invention to the particular mechanisms herein disclosed.

My improved mechanism may be operated from any suitable source of power and in the particular construction illustrated, I have shown an electric motor *25* which is arranged within the casing or housing *A*. This motor is mounted upon a base *26* and any suitable means may be employed for readily connecting and disconnecting the motor with my improved container advancing mechanism. By way of illustration, I have shown a motor drive mechanism such as is disclosed in my copending application No. 112,107 filed Nov. 21, 1936, by means of which a pulley secured on the motor shaft may be moved into and out of driving engagement with a belt. For this purpose, the base *26* of the motor is pivoted at one end thereof upon lugs *27* formed on the housing *A*, a pivot rod *28* extending through these lugs and through a part of the base *26*. By swinging the motor upwardly about the axis of the pivot rod *28*, a driving pulley *29* on the motor shaft may be moved out of driving engagement with the belt *30* for interrupting the operation of the mechanism as shown in Figs. 10 and 15, and when the motor is lowered, the driving pulley *29* engages the belt *30*, as shown in Figs. 16 and 17. Any other suitable clutch means may be provided for connecting and disconnecting the motor and the mechanism. In connection with the particular clutch means shown, means may be employed to hold the belt out of engagement with the driving pulley *29*, as described in my copending application No. 112,107 filed Nov. 21, 1936, but such belt holding means are omitted from the accompanying drawings for the sake of clearances.

The belt *30* cooperates with a driven pulley *31* mounted on a shaft *32* which may be suitably journaled in any desired manner on the frame or housing *A*, for example, on downwardly extending brackets *33* and *34*, Fig. 6. The shaft *32* may impart motion to my improved mechanism in any suitable or desired manner, for example, through the medium of a worm *35* meshing with a worm gear *36* mounted to rotate about the axis of a shaft *37* extending transversely of the housing *A* of the machine and hav-

ing its ends secured in lugs or projections 38 and 39.

The raising and lowering and also the swinging of the table D are preferably effected by means of cams which are positioned in correct timing relation to each other and all of which may be rotated by means of the gear 36 about the axis of the shaft 37. In the particular construction illustrated, I have provided a cam 42 for raising the table and for controlling the lowering of the same. The shaft 37 is suitably connected with the worm gear 36 for this purpose. This cam cooperates with a lever 43, one end of which is pivoted to lugs or projections 44 of the housing A and the other end of which is pivotally connected at 46 to the lower end of an upright rod or bar 45, the upper end of which is connected with the table D. The middle portion of the lever 43 preferably has an anti-friction roller 47 which bears on the face of the cam 42, Figs. 6, 10 and 14. In the position of the parts shown in Fig. 6, the roller 47 rides on the highest part of the cam 42 and consequently, through the medium of the lever 43 and connecting rod or bar 45, the table is shown in its highest position.

The connection between the rod or bar 45 and the table D may be effected in any suitable or desired manner. In the particular construction shown, see particularly Fig. 6, this rod or bar extends upwardly into a stationary central tubular supporting pillar 50 of the column B. The lower end of this pillar is rigidly secured in a substantially circular base or flange 51 of the housing or frame member A and the upper part of the pillar 50 has an annular cap member 52 rigidly secured thereto, on the upper portion of which the base of the tank C rests. This column, therefore, supports the tank C in fixed relation to the base or frame member A. The upper end of the connecting rod or bar 45 has a transversely extending bearing sleeve 53 which is preferably formed integral therewith. Within this sleeve is journalled a transversely extending pin 54, the ends of which extend through upright slots 55 formed in the pillar 50, see also Fig. 11. The outer ends of the pin 54 are provided with rollers 57 upon which the lower circular flange of a cylindrical bearing part or sleeve 58 rests. This sleeve is slidably and rotatably arranged about the pillar 50 and is suitably secured through the medium of another cylindrical member 59 to the table D. Consequently, when the connecting rod or bar 45 is raised or lowered, the table D, which rests by gravity upon the rollers 57, is also raised or lowered to the same extent and because of the rolling contact between the rollers 57 and the cylindrical sleeve 58, the table is free to rotate independently about the elevating and lowering means, and about the pillar 50.

In order to properly guide the table D in its vertical and rotary movement on the pillar 50, it is desirable to provide another bearing on the pillar below the rollers 57, and consequently, the cylindrical table supporting part 59 is provided with a lower cylindrical bearing portion 60 which engages the pillar 50 below the table D.

The cam 42 which effects the raising and lowering of the table D may be connected with the worm gear 37 in any suitable or desired manner and in the construction shown, the cam is secured to or formed integral with a sleeve 66, Figs. 10 and 14, which extends about the shaft 37 between the lugs 38 and 39, and the worm wheel 36 has its hub portion arranged about the bearing sleeve 66 and is secured to the cam 42 by means of a screw or

bolt 67. The shaft 37 may be held in fixed position by means of a pin 64 extending through the shaft and the lug 38. Any other connection between the cam and the worm gear may, of course, be provided, if desired.

The mechanism for rotating the table to advance the containers from one station to another may be effected in any suitable or desired manner, and in the construction illustrated, I also effect this movement by means of a cam which is in fixed relationship to the cam 42. For example, the cam for effecting rotation of the table may be formed integral with a side of the gear wheel 36, and in the construction illustrated, I have provided on a side of the worm gear 36 a pair of laterally extending flanges or webs 70 and 71 which are spaced apart and forming between them a cam slot or groove in which a roller 72 pivotally mounted on a lever 73 may operate. The lever may be pivoted at 74 on an upwardly extending lug formed on the bottom of the housing A and the cam groove between the flanges 70 and 71 is of such shape as to impart to the lever 73 the desired movement. The lever 73 is preferably connected by means of one or more links 74 to a slidable rack 75 suitably guided on the housing A to slide in a lengthwise direction. This rack 75 engages with a gear 76 which is secured to a sleeve 77 rotatably arranged about the pillar 50 see Figs. 6 and 13. In the construction shown, the gear is arranged in an annular recess formed in the upper face of the boss or flange 51 in which the lower end of the pillar is secured. The sleeve 77 is provided with suitable means for forming a driving connection with the cylindrical bearing member 60 which is secured to the table, when the table and the cylindrical part 60 are in their lowest position. For example, in the construction illustrated, the upper edge of the sleeve 77 is provided with a plurality of upwardly extending projections or teeth 78 which are adapted to enter into corresponding recesses or depressions 79 formed in the lower edge of the cylindrical bearing member 60. Consequently, when the table D is in its lowest position, the sleeve 77 will become interlocked with the lower end of the bearing member 60 and at the same time, the cam flanges or projections 70 and 71 will swing the lever 73 in a direction to move the rack bar 75 in such a manner as to turn the sleeve 77 through an arc of a circle sufficient to move the table D to advance the containers thereon from one station to the next. When the circular movement of the table D is completed, the table is again raised through the action of the cam 42 and lever 43, as has already been described, to position the containers in correct relation to the bottle filling and capping mechanisms.

Means may be provided to further insure the correct registration of the containers with the filling and capping mechanisms. In the construction shown for this purpose, a key and slot connection is provided between the table and a fixed part of the machine, which interengage when the table moves into its upper position. In the machine illustrated, Figs. 6 and 7, one or more upright grooves or slots 80 are arranged on a part of the table, for example, on the bearing sleeve 58 or the cylindrical part 59. Suitable keys 81 are arranged on a depending cylindrical part 82, the upper end of which is rigidly secured to the cap member 52. The cylindrical part 82 extends downwardly over and around the bearing sleeve 58 and the cylindrical 75

member 59 when the table is in its upper position, and forms a guard which covers and protects these parts. The key members 81 may have downwardly converging side faces and the upper 5 ends of the side walls of the upright slot 80 may diverge upwardly so that if the table D is not moved into exactly the correct position by means of the rack 75 and the gear 76, the entrance of the key member 81 into the upright slot 80 will 10 cause the table D to be turned to the necessary extent to cause the bottles to correctly register with the filling and capping devices. The key and slot arrangement described has the advantage also of holding the table positively against 15 any turning movement when the containers are being filled, capped or otherwise operated upon. The slots are of sufficient length so that the keys enter the same immediately after the lower bearing member 60 has passed out of engagement 20 with the rotatable sleeve 77. Any other suitable means for ensuring the correct positioning of the table with reference to the stationary capping and filling devices may, of course, be employed, if desired.

25 The lever 73 of the table rotating mechanism may also be used to actuate the capping devices of the machine and in the machine illustrated a link 83, Figs. 12 and 14, is pivotally connected with the lever 73 at 84. The other end of this 30 link is pivotally connected with an arm 85 secured to the lower end of an upright rod or shaft 86 which extends upwardly through the pillar 52. At its upper end the rod or shaft is provided with an arm 87, by means of which the capping devices may be actuated as described in my aforesaid application No. 112,106.

As has been stated, the machine can readily be adapted to operate on bottles of different sizes and in order to enable the machine to operate at maximum capacity, the mechanism should be operated at such speed as to move the bottles and the tables supporting the same from one position to another at near the maximum speed without tipping the bottles over and without spilling any of the contents when the movement of the same is accelerated and decelerated. This maximum speed is practically the same for bottles of different sizes. It is obvious, however, that considerably longer time is occupied in filling large bottles, such for example as the quart size, than is required for filling pints, and half-pints require still shorter filling periods. If the operation of the machine were entirely controlled by means of cams, it would, consequently, be necessary to operate the table so that the same will remain in stationary or fixed position for a sufficient length of time to enable the filling mechanism to fill the largest containers and this, consequently, would make it necessary to keep the 45 smaller containers in their filling and capping positions for the same length of time as the largest containers, even though the smaller containers would be filled long before such time interval had elapsed. In order to overcome this difficulty, I provide means whereby the operation of the cam mechanism is discontinued when the containers are placed in positions to be operated upon or filled, and this may, for example, be accomplished by disconnecting the motor or other 50 source of power from the cam mechanism during at least a part of the time while the containers are being filled. I also provide means whereby this time interval can be varied so that the table will be in the proper position for a shorter 55 length of time when operating on small contain-

ers than when operating on larger containers, and the means, briefly stated, include mechanism operated by the cam mechanism for disengaging the power supply thereto when the cam mechanism reaches a position in which the table 5 D is in its upper position, and an adjustable time-controlled device whereby the motor or other power is again placed into driving connection with the cam mechanism after the desired time interval has elapsed. 10

In the particular construction shown for this purpose, the rotatable cam member is provided on a portion thereof with an outwardly projecting cam part 88 which may, for example, be formed on the outer face of the flange or web 15 70. This cam 88 cooperates with a roller 89 pivoted on an arm 90 rigidly mounted on a sleeve 91, Fig. 10, journalled on a fixed shaft 91a, the ends of which may be secured in the frame or housing A, in any suitable manner. On this sleeve are arranged or rigidly secured two arms 92 and 93 extending in opposite directions from the sleeve 91, and the arm 92 is so arranged that when the outwardly extending cam portion 88 20 engages the roller 89 and swings the arm 90 to the left in Figs. 15 to 17, the arm 92 will swing upwardly.

Any suitable releasable means may be provided for causing movement produced by the cam part 88 to disconnect the motor 25 from driving engagement with the cam member, and in the construction shown for this purpose, the outer end of the arms 92 is provided with a suitable aperture through which a bolt or link 95 may extend, and this bolt or link 95 is secured to a hook 35 member 96 having a hook-shaped part or shoulder 97 formed thereon which is adapted to engage an upwardly extending arm or part 98 of the base 26 of the motor. The upper end of this part of the motor base is provided with a downwardly facing hook or shouldered part adapted 40 to engage with the upwardly facing hook or shouldered part 97 of the hook member 96. Consequently, when the arm 92 moves upwardly, the motor base 26 and the motor supported thereby 45 will also be moved upwardly because of the engagement of the hook member 96 with the upwardly extending projection 98 of the base. This upward movement of the base moves the motor pulley 29 out of engagement with the belt 30 so 50 that further transmission of power to the cam mechanism is interrupted.

Any suitable time controlled means may be provided for again establishing a driving connection between the motor and the cam mechanism 55 and this may be accomplished by releasing the connection or means by which the driving connection is rendered inoperative, for example, by disengaging the hook part 96 from the upwardly extending part 98 of the base, so as to 60 permit the motor base to swing downwardly about its pivotal connection with the lugs 27 of the frame or housing, into driving position in which the pulley 29 again engages the belt 30. In the particular construction illustrated, I have 65 provided a dash pot mechanism for controlling the time interval during which the bottle supporting table D remains in its upper position and this mechanism is actuated through the medium of the arm 93, which in the construction shown 70 is pivotally connected at 100 to an upwardly extending rod or link 101. The lower end of this link is preferably bifurcated, as shown at 102 and formed integral with or secured to a spring compressing member, such as substantially circular 75

base part 103, the lower face of which engages a resilient or compressible member, such for example as a coil spring 104. The lower end of the spring or compressible member 104 bears 5 against the bottom of the plunger or piston 106 which is arranged in a cylinder 107. The plunger 106 and cylinder 107 together form a dash pot for controlling the time interval during which the table D remains in its upper position and it will 10 be noted that the plunger or piston 106 is moved downwardly through the medium of the spring or resilient member 104.

The dash pot preferably operates in an oil bath contained in a suitable tank or reservoir formed 15 in the base of the frame member A, this member being provided with a transverse partition wall or dam 110 formed integral with the base and extending upwardly therefrom and forming with a part of the base an oil reservoir or case 111 containing sufficient oil or other lubricant so that the gear 36 and cams mounted thereon dip into the same as clearly shown in Figs. 6 and 12 and for convenience, the cylinder 107 is arranged 20 with its lower portion extending into the oil reservoir 111, although it will be obvious that any other arrangement of the dash pot may be employed and the same may operate on other liquid than the lubricant in the base of the machine. The construction shown, however, is desirable in that the oil bath serves not only as a supply for the dash pot mechanism, but also serves to lubricate many of the parts of the machine.

The cylinder 107 of the dash pot is provided 25 on a side thereof with an extension 112 forming a valve housing which has a downwardly directed inlet opening 113 which may, if desired, be formed in a removable screw plug 114 and the opening 113 is closed by a suitable check valve, 30 for example, a ball 115 which may seat in the upper end of the plug 114 about the aperture 113 therein. Consequently, when the plunger or piston 106 is moved upwardly as will be hereinafter described, oil or other lubricant from the reservoir 111 is drawn upwardly through the opening 113, lifting the valve 115 from its seat, and then 35 enters into a passage 116 in the lateral extension 112 of the cylinder. This opening 116 is connected through suitable grooves or slots 118 in 40 the wall of the cylinder with the cylinder head below the plunger 106.

The discharge of liquid from the dash pot when the plunger 106 is moved downwardly by the action of the spring 104 may be controlled 45 in any suitable or desired manner, and in the construction shown, see particularly Figs. 19 and 20, a relatively small discharge passage is provided in the valve housing 112, including a horizontally extending hole or recess 120 connecting 50 with a downwardly extending passage or hole 121, the passage 120 connecting with the interior duct or passage 116. The passage 120 in the particular construction shown is controlled by means of a needle valve 122 having a threaded 55 part 123 engaging in a correspondingly threaded aperture in the extension 112 of the cylinder 107. Consequently, by turning the needle valve 122 about its axis, the same will be moved by means 60 of the screw thread 123 toward and from the end 65 of the passage or hole 120, thus decreasing or increasing the discharge opening to this passage. Obviously when this discharge passage is restricted or reduced, the piston 106 will move 70 downwardly in the cylinder 107 at a slower rate 75 than when the needle valve is opened to a greater

extent, and by correct adjustment of the needle valve, the time interval during which the table D remains in its upper position can be accurately controlled.

Any suitable or desired means for adjusting 5 the needle valve may be provided, and in the particular construction illustrated, see particularly Figs. 1 and 19, the needle valve 122 has a stem portion 125 which extends out of the housing or casing A, for example, through a suitable packing nut 126, and at the outer end of the stem 125, a lever 127 may be rigidly secured in any suitable manner. This lever may, as illustrated in Fig. 1, extend upwardly along a side of the frame A of the machine and along the outer edge of a shelf 128 or ledge 128 which is suitably secured to the side of the frame member A. The lever 127 may be held in any adjusted position in any suitable or desired manner, and in the particular construction illustrated, the lever may be yieldingly pressed against the edge of the shelf 128 by means of a bar 130. In the construction shown in Figs. 1 and 5, this bar is of angle-shaped cross section and is held in correct relation to the shelf 128 by means of two or more bolts 131 having their 10 threaded ends secured in threaded holes in the edge of the shelf 128 and extending loosely through suitable apertures in the upwardly extending flange of the bar 130. The bar is pressed toward the edge of the shelf 128 by means of coil 15 springs 132 arranged between the bar 130 and the heads of the bolts 131. Each bolt preferably also has a spring 133 arranged about a portion of the same and positioned between the edge of the shelf 128 and the bar 130. The springs 132 are 20 stronger than the springs 133 so as to urge the bar 130 against the lever 127 and thus frictionally hold the lever between this bar and the edge of the shelf 128. The other spring 133 merely serves to space the bar 130 from the edge 25 of the table to a sufficient extent so that the bar 130 will lie approximately parallel to the adjacent edge of the shelf 128, which in turn helps to hold the lever 127 more positively in any position in which it may be set. The operator of the 30 machine can, consequently, control the time interval during which the table D remains in its upper position by suitably positioning the lever 127.

The plunger or piston 106 of the dash pot may 35 be connected through any suitable or desired mechanism with the hook member 96 in such a manner that when the plunger has moved downwardly in its cylinder to a certain extent, the hook member 96 will disengage the motor 50 to permit the same to move into its driving position. In the particular construction shown for this purpose, the plunger or piston is provided with an upwardly extending piston rod 55 60 65 70 75 80 85 90 95 100 105 110 115 120 125 130 135 140 145 150 which a pin 146 extends, this pin being secured to the hook member 96.

It will be obvious by an inspection of Figs. 15, 16 and 17 that when the plunger 106 is in its upper position, as shown in Figs. 15 and 17, the downwardly extending arm 143 of the bell crank lever will draw the connecting link 144 to the right so that the hook or shouldered portion 97 will be yieldingly drawn into engagement with the upwardly extending part 98 of the motor base. As the plunger 106 moves downwardly under the action of the spring 104, the nut 138 will engage the arm 142 of the bell crank lever and move it downwardly, thus causing the arm 143 to swing to the left until it has moved the connecting link 144 to the left to such an extent that the shoulder or hook 97 disengages the upward extension 98 of the motor base and permits the motor to swing by gravity into its driving position. This will cause the gear 36 and cam 88, as well as the other cams, to be turned. When the high spot of the cam 88 moves out of engagement with the roller 89, the arms 92 and 93 move into the positions shown in Fig. 17, in which the hook member 96 carried by the arm 92 is lowered into a position in which it can readily engage the upward projection 98 of the motor base when the cam 88 again moves around into the position shown in Figs. 15 and 16. The arm 93 when in the upper position as shown in Fig. 17, moves the rod 101 upwardly so that the spring compressing base portion 103 of this arm engages the lower nut 137 of the rod 136 and moves the plunger 106 upwardly, drawing a supply of liquid into the cylinder 107 past the check valve 115. In order to insure the swinging of the arms 92 and 93 into the position shown in Fig. 17, a spring 148 is provided, one end of which may be secured to the pivot member or pin 100, while the other end may be secured to any suitable fixed part of the frame, such for example as a cross member or web 149, see Figs. 6 and 11.

It will be noted that by means of the releasable connection between the hook member 96 and the motor base, the time controlled mechanism causes the motor to move quickly and positively into driving position, so that the mechanism is operated instantly. By using the gradual and slow movement of the parts of the time controlled mechanism to act on the motor through the medium of the releasable connection to produce a rapid movement of the motor into driving position, the wear of the driving pulley 29 on the driving belt is reduced to a minimum. This wear is further reduced by the fact that at the time when the pulley 29 moves into engagement with the belt 30, the table actuating mechanism is not called upon to do any work, since the first step after starting the mechanism is to lower the table, which is effected by gravity.

The inclined slot 145 in the connecting link 144 serves as a yielding connection between this link and the hook member 96, so that if the hook member in moving downwardly strikes the projection 98, it can move to the left as shown in Fig. 17, in which case the pin 146 can also move to the left. The inclination of the slot 145 together with the weight of the link 144 urges the hook member 96 to the right in position to engage the hook of the projection 98 of the motor base.

Means are preferably provided whereby the time interval during which the table D is in its upper position may be under the control of the operator, rather than the time controlled mech-

anism. Control means of this kind can readily be applied to the mechanism herein described, for example, I have provided at the side of the housing A of the machine a foot pedal 154 which is secured intermediate of its ends on a rock shaft 155 which extends into the housing or frame A of the machine. On the inner end of this rock shaft is provided an arm 156 which may be swung by means of the foot pedal either into an upper or inclined inoperative position, as shown in Figs. 6 and 8, or into an approximately horizontal position, as shown in Fig. 9. The foot pedal preferably has a laterally extending arm 157 which, as shown in Fig. 1, is marked "stop" and which when depressed will move the arm 156 into the substantially horizontal position. The foot pedal also has at its other extremity another arm or lateral extension 158 marked "start", on which the operator may step to move the foot pedal to the other limit of its movement in which the arm 156 is swung into its inoperative or inclined position as shown in Figs. 6 and 8, whereupon the machine is again operated under control of the dash pot.

Any suitable means may be provided for yieldingly holding the foot pedal and the arm 156 in either position and for this purpose, the base of the frame or housing A of the machine may be provided with an upwardly extending lug 160 which may be bored to receive a plunger 161 urged outwardly by means of a spring 162, a screw plug 163 closing the lower end of the aperture which extends through the lug. The plunger 160 bears against portions of the arm 156 which may be flattened as shown in Fig. 6, so that the foot pedal will normally be held in either of its two extreme positions. The downward movement of the part 158 may be limited by the frame A of the machine and the movement of the foot pedal in the opposite direction may be limited by means of a shoulder or stop edge 164 formed on the arm 156.

In order to cooperate with the arm 156, the connecting link 144 is provided with an extension 166, the outer end of which is rounded or curved so as to readily cooperate with the arm 156. This connecting link 144, as clearly shown in Fig. 10, is bifurcated to straddle the hook member 96 and the extension 166 is formed on one of the legs of this bifurcated member. When the arm 156 is in its operative or lowered position as shown in Fig. 9, it engages the end of the extension 166 of the connecting member or link and when in this position would prevent the connecting link 144 from moving in a direction to disconnect the hook member 96 from the upward extension 98 of the motor base. Consequently, the table D will remain in its upper position until positively released by swinging the foot pedal into a position to move the arm 156 out of engagement with the extension 166, whereupon the spring 148 will quickly swing the arm 92 downwardly to lower the hook member 96. The machine will then operate to lower the table and advance the same to move the bottles to their next stations and then again to raise the table into filling and capping position. It will be obvious that the foot pedal may be actuated to stop the operation of the table in its upper position even before the table reaches such position and the machine will, nevertheless, continue its operation until the table reaches the upper position, whereupon the cam 88 stops the mechanism in the manner described, so that the same will not start until the foot pedal is again actuated.

170 represents a cylindrical guard extending around the lower portion of the pillar 50. This guard may be formed integral with the top or cover plate 171 of the housing A. Another 5 cylindrical guard 172 secured to the bearing member 59 of the table D is arranged in telescopic relation about the guard 170, so that water or other liquid used in cleaning the machine will not enter the housing A. In the same manner, 10 the cylindrical part 82 acts to keep out liquid and foreign matter.

It will be noted that by means of the mechanism described, the machine may be operated at maximum capacity regardless of the size of the 15 packages or containers which are being operated upon. If the machine is operating on small packages, the time controlled or dash pot mechanism can be adjusted so that the packages or containers remain in their filling positions only 20 long enough to fill the same. The time interval during which the packages or containers remain in their filling positions can be controlled not only by adjusting the lever 127, but further adjustments can be effected by changing the 25 relationship between this lever and the needle valve 122. Since the adjustment of the time period during which the packages or containers remain in their filling positions does not affect the rate 30 of movement of the mechanism for advancing the articles from one position to another, it is obvious that packages or containers of all sizes may be advanced from one position to another at the maximum speed.

The machine described has the advantage that 35 it may be used to operate automatically so that it is only necessary for the operator to remove the containers which have been filled and capped or otherwise operated upon by the machine from the table D and replace them by containers to 40 be operated upon. If the machine is changed to operate on containers of a different size, it is merely necessary to operate the hand lever 127 to adjust the machine for the different size of containers. If the operator desires to stop the 45 operation of the machine without stopping the motor or to prolong the period during which the containers are in position to be operated upon, it is merely necessary to step upon the arm 157 of the foot pedal 154, or if the operator desires 50 to control the operation of the machine, he can move the foot pedal 154 into stop position until he has removed the filled containers and replaced them by empty ones and until he sees that the containers in the filling station are filled, where- 55 upon he can move the foot pedal 154 into starting position by depressing the arm 158 thereof. If the time controlled mechanism has moved into position to move the motor into driving position, the link 144 will immediately move the hook 60 member 96 out of engagement with the projection 98 of the motor base whereupon the table advancing mechanism goes into operation. If the foot pedal is moved into starting position before the containers have been filled and be- 65 fore the time controlled mechanism is in position to move the motor into driving connection with the table advancing cam mechanism, then the starting of this mechanism will be delayed until the time controlled mechanism has moved 70 through its cycle. Consequently, the operator need not be particular to actuate the foot pedal at the right time but can actuate it sooner without resulting in incomplete filling of or other operation on the containers.

75 I claim as my invention:

1. A machine for operating on containers, including a container supporting table movable in a direction to advance the containers from one position to another and movable in another direction to place the containers into a position to be operated upon, power driven mechanism for imparting said movements to said table, means for interrupting the operation of said power driven mechanism when said table is in said position in which the containers may be operated upon, 10 time controlled means for rendering said table moving mechanism again operative, and means for adjusting said last mentioned means to vary the time interval during which said table remains in said position in which the containers 15 may be operated upon.

2. A machine for operating on containers, including a container supporting table, mechanism for moving said table to advance the containers and to place the same into position to be operated upon, means for stopping said table moving mechanism after said containers have been placed in position to be operated upon, a dash pot which is placed into operation when said table is stopped in said position, means actuated by said dash pot for again starting the operation of said mechanism, and means for adjusting said dash pot to vary the time interval during which said table is stopped in said position.

3. A machine for operating on containers, including mechanism for placing a container into a position to be operated upon, means for stopping the operation of said mechanism when the container is in said position, time controlled mechanism for again starting the operation of said container placing mechanism, and means for adjusting said time controlled mechanism to vary the time during which the container is in said position.

4. A machine for operating on containers, including mechanism for advancing the containers on the machine and placing the same in position to be operated upon, a motor for driving said mechanism, means for discontinuing the operation of said mechanism by said motor when a 45 container is placed in said position, and adjustable time controlled means for again establishing the operation of said mechanism by said motor after a desired time interval to cause said mechanism to move said container from said position and to move another container to said position.

5. A machine for operating on containers, including a table for supporting the containers, mechanism for moving said table in a rotary direction to advance the containers from one position to another, and to raise said containers into positions in which the containers are operated upon, means for rendering said mechanism inoperative when said containers have been placed into their raised positions, and adjustable time controlled mechanism for causing said mechanism to be again operated after a lapse of the desired time interval.

6. A machine for operating on containers, including a table for supporting the containers, mechanism for moving said table in a rotary direction to advance the containers from one position to another, and to raise said containers into positions in which the containers are operated upon, a source of power for operating said mechanism, means actuated by said mechanism after a container has been moved into a position to be operated upon for interrupting the transmission of power to said mechanism, time con- 75

- trolled means which are actuated by said mechanism when the supply of power thereto is interrupted, means actuated by said time controlled means for resuming the transmission of power to said mechanism, and means for adjusting said time controlled means to vary the time interval during which said containers remain in position to be operated upon.
7. In a machine for operating on containers, an intermittently operated cam controlled mechanism for moving containers into and out of a position to be operated upon, a source of power having a driving connection with said cam mechanism, means actuated by a part on said cam mechanism for interrupting said driving connection, a time controlled device which is placed into operation by said part, and means operated by said time controlled device for again establishing a connection between said source of power and said cam mechanism independently of said part.
8. In a machine for operating on containers, the combination of a cam mechanism for moving containers into and out of a position to be operated upon, a source of power arranged to be connected with and disconnected from said cam mechanism, releasable means for disconnecting said source of power from said cam mechanism, a part in said cam mechanism for actuating said releasable means to disconnect said source of power from said cam mechanism, an adjustable time controlled device which is placed into operation when said source of power is disconnected from said cam mechanism, and a connection between said time controlled device and said releasable connection for releasing the same after the lapse of a predetermined time interval to again establish connection between said source of power and said cam mechanism.
9. In a machine for operating on containers, the combination of a cam controlled mechanism for moving containers into and out of a position to be operated upon, a motor movable into a position to transmit power to said mechanism and into another position in which said motor is disconnected from said mechanism, means for moving said motor into said other position when said containers are in positions to be operated upon, a time controlled mechanism which operates when said containers are in position to be operated upon, and means actuated by said time controlled mechanism for moving said motor into driving position after lapse of the desired time interval.
10. In a machine for operating on containers, the combination of a mechanism for moving containers into and out of a position to be operated upon, a motor, a driving belt for connecting said motor with said mechanism, a releasable connection between said mechanism and said motor for moving said motor out of driving relation to said belt when said containers are in positions to be operated upon, a time controlled mechanism which operates when said containers are in position to be operated upon for releasing said connection after a predetermined time interval to permit said motor to move into engagement with said driving belt.
11. In a machine for operating on containers, the combination of mechanism for moving containers into and out of a position to be operated upon, a motor having a driving connection with said mechanism, means operated by said mechanism for interrupting said driving connection when a container is in position to be operated upon, a dash pot which is placed into operation by said mechanism when a container is in position to be operated upon, and means operated by said dash pot after a desired time interval to again establish the driving connection between said motor and said mechanism.
12. In a machine for operating on containers, the combination of mechanism for moving containers into and out of a position to be operated upon, a motor having a driving connection with said mechanism, means operated by said mechanism for interrupting said driving connection when a container is in position to be operated upon, a dash pot, a spring for actuating said dash pot, means operated by said mechanism when a container is placed into position to be operated upon for applying pressure to said spring to operate said dash pot, and means actuated by said dash pot to again establish a driving connection between said motor and said cam mechanism after a lapse of a desired time interval.
13. In a machine for operating on containers, the combination of mechanism for moving containers into and out of a position to be operated upon, a motor having a driving connection with said mechanism, means operated by said mechanism for interrupting said driving connection when a container is in position to be operated upon, a dash pot which is placed into operation by said mechanism when a container is in position to be operated upon, means operated by said dash pot after a desired time interval to again establish the driving connection between said motor and said mechanism, a part having a passage leading to said dash pot, and a valve controlling said passage for varying the time interval during which a container is in a position to be operated upon without varying the speed of said mechanism.
14. A machine for operating on containers, including mechanism for advancing the containers on the machine and placing the same in position to be operated upon, a motor for driving said mechanism, means for discontinuing the operation of said mechanism by said motor when a container is placed in said position, adjustable time controlled means for again establishing the operation of said mechanism by said motor after a desired time interval to cause said mechanism to move said container from said position and to move another container to said position, and means adapted to be actuated by the operator for stopping the operation of said time controlled means.
15. In a machine for operating on containers, the combination of a mechanism for moving containers into and out of a position to be operated upon, a motor having a driving connection with said mechanism, releasable means actuated by a part of said mechanism for interrupting said driving connection, a time controlled device which operates when a container is in a position to be operated upon, means operated by said time controlled device for releasing said releasable means to again establish a driving connection between said motor and said mechanism, and means adapted to be actuated by an operator to prevent the releasing of said releasable means by said time controlled device.
16. In a machine for operating on containers, the combination of a mechanism for moving containers into and out of a position to be operated upon, a motor movable into and out of driving connection with said mechanism, a hook member actuated by a part of said mechanism for releas-

ably engaging said motor and to move the same out of driving connection, a time controlled device which operates when a container is in a position to be operated upon, a link connecting said hook member and said time controlled mechanism for releasing said connection between said hook member and said motor, and means adapted to be actuated by an operator to hold said link against movement in a direction to release said hook member from said motor.

17. In a machine for operating on containers, the combination of a rotatable and vertically movable table for supporting containers, mechanism for actuating said table including a cam for raising and lowering said table, a second cam for imparting rotary motion to said table, a motor for driving said cam mechanism, a disengagable driving connection between said motor and said cam mechanism, means actuated by said cam mechanism for disengaging said driving connection when said table has been moved vertically into a position in which a container may be operated upon, and means for actuating said driving connection to again drive said cam mechanism from said motor after operation on said container is completed.

18. In a bottle filling and capping machine, the combination of a housing, a pillar extending upwardly from said housing, bottle filling and capping devices mounted on the upper end of said pillar, a table mounted to rotate about said pillar and to move vertically thereon, mechanism in said housing for raising and lowering said table and for imparting rotary motion thereto, a motor for operating said mechanism, a releasable driving connection between said motor and said mechanism, means operated by said mechanism for interrupting said driving connection, and means for reestablishing the driving connection after bottles have been filled and capped.

19. A machine for operating on bottles, including a rotary and vertically movable bottle supporting table, mechanism for imparting rotary and vertical movement thereto, a motor, transmission means connecting said motor with said mechanism, releasable means actuated by said mechanism for interrupting said transmission means, and means for releasing said releasable means to again establish a driving connection between said motor and said mechanism.

20. In a machine for operating on containers, the combination of a rotary and vertically movable container supporting table, a mechanism for rotating said table, including a rotary gear, a rack meshing with said gear, cam controlled means for reciprocating said rack to turn said gear through a portion of a revolution, said table and said gear having interlocking portions which engage when said table is lowered, and another cam, arranged in fixed relation to the cam of said cam controlled means, for lowering said table when said gear is turned through an arc of a circle in one direction and for raising said table out of engagement with said gear when said gear is turned in the opposite direction.

21. A bottle filling and capping machine, including a housing, a pillar rigidly secured to said housing and extending upwardly therefrom, a bottle supporting table having a cylindrical bearing on the exterior of said pillar, a sleeve journalled about the lower portion of said pillar and movable at intervals through a portion of a revolution and having parts adapted to engage with a part of the bearing of said table when said table is in lowered position to impart rotary movement

thereto, and interlocking parts on a fixed part of the machine and another portion of said table bearing which move into engagement when said table is raised to prevent rotation of said table when out of engagement with said sleeve.

22. A bottle capping and filling machine, including a rotary and vertically movable bottle supporting table, a cam, means actuated by said cam and connected with said table for raising and lowering the same, a rotatable sleeve, a second cam, means actuated by said second cam and connected with said sleeve for imparting rotation thereto when said first cam has moved said table into its lower position, and cooperating parts on said sleeve and said table, whereby rotation of said sleeve is imparted to said table when said table is in lowered position.

23. A machine for operating on containers, including a container supporting table, mechanism for moving said table to advance the containers and to place the same into position to be operated upon, means for stopping said table moving mechanism after said containers have been placed in position to be operated upon, and means adjustable to render said table moving means operative after lapse of the desired time interval.

24. A machine for operating on containers including mechanism for advancing the containers on the machine and placing the same in position to be operated upon, a motor for driving said mechanism, means for disconnecting said motor from said mechanism when the container is in said position, and adjustable time controlled means for again connecting said motor with said mechanism after a lapse of the desired time interval to move the container from said position and to place another container into said position.

25. In a machine for operating on containers, an intermittently operated cam controlled mechanism for moving containers into and out of a position to be operated upon, a source of power having a driving connection with said cam mechanism, releasably connected members movable in a direction to interrupt the transmission of power to said cam mechanism, a part on said cam mechanism for operating said members to interrupt the transmission of power to said cam mechanism, and an adjustable time controlled device which is placed into operation by said part and which disconnects said releasably connected members to resume the transmission of power to said cam mechanism.

26. A machine for operating on containers including mechanism for advancing the containers on the machine and placing the same in position to be operated upon, a motor for driving said mechanism, means for disconnecting said motor from said mechanism when the container is in said position, time controlled means for again connecting said motor with said mechanism after a lapse of the desired time interval to move the container from said position and to place another container into said position, and means for adjusting said time controlled means in accordance with the time required to operate on said containers to vary the time interval during which said containers are in position to be operated upon without varying the speed of operation of said container advancing mechanism.

27. In a machine for operating on containers, the combination of a mechanism for moving containers into and out of a position to be operated upon, a motor movable into and out of driving connection with said mechanism, a hook member

actuated by a part of said mechanism for releasably engaging said motor and to move the same out of driving connection, a time controlled device which operates when a container is in a position to be operated upon, a link connecting said hook member and said time controlled mechanism for releasing said connection between said hook member and said motor, and means adapted to be actuated by an operator to hold said link against movement in a direction to release said hook member from said motor.

28. In a machine for operating on containers, the combination of a mechanism for moving con-

5 tainers into and out of a position to be operated upon, a motor movable into and out of driving connection with said mechanism, a hook member actuated by a part of said mechanism for releasably engaging said motor and to move the same out of driving connection, a time controlled device which operates when a container is in a position to be operated upon, and a link connecting said hook member and said time controlled mechanism for releasing said connection 10 between said hook member and said motor.
